(57) **CLAIM**

The ornamental design for a five-bladed ceiling fan, as shown and described.

DESCRIPTION

FIG. 1 is an elevated, front-left perspective view of the new design for a five-bladed ceiling fan;

FIG. 2 is a lowered, front-right perspective view of the design of FIG. 1;

FIG. 3 is a rear elevational view of the design of FIG. 1;

FIG. 4 is a top plan view of the design of FIG. 1;

FIG. 5 is a right side elevational view of the design of FIG. 1;

FIG. 6 is a left side elevational view of the design of FIG. 1;

FIG. 7 is a front elevational view of the design of FIG. 1; and,

FIG. 8 is a bottom plan view of the design of FIG. 1. Broken lines included within the drawings (FIGS. 1, 4) depict environmental subject matter only and form no part of the claimed design.
